PAPER FEED FOR TOWEL DISPENSERS

Philip A. Wooster, San Rafael, Calif.

Application December 31, 1941, Serial No. 425,175

8 Claims. (Cl. 271—2.3)

1

This invention relates to dispensing devices for paper towels and the like, and particularly to paper feeding mechanism by means of which a roll of toweling is supported in and advanced from a dispensing cabinet.

It is the object of the present invention to provide paper supporting and feeding means for a towel dispensing cabinet which will insure proper feeding of an uncrumpled and un torn length of toweling upon each dispensing operation of the cabinet, and which will insure against jamming or clogging of the paper within the cabinet.

A further object of the invention is the provision of a dispensing device in which the operating mechanism and the most vital parts of the paper feeding mechanism are protected against tampering or adjustments by unauthorized persons, even when the dispenser is opened for the purpose of replenishing the towel supply therein.

A still further object is the provision of paper feeding mechanism which advances a length of toweling to a position where it may be torn from a continuous roll upon each dispensing operation of the cabinet, and to prevent tearing of the paper within the cabinet at any point which is likely to cause the paper to become jammed or crumpled or torn during the next dispensing operation.

Further objects and advantages of the invention are made apparent in the following specification, wherein detailed reference is made to the accompanying drawings.

In the drawings—

Fig. 1 is a vertical sectional view taken through a towel dispenser constructed in accordance with the present invention;

Fig. 2 is a front elevation of the towel dispenser with the lower front portion of the cover broken away to illustrate details of construction of the forward rolls, tearing edge, and associated parts;

Figs. 3, 4 and 5 are sectional views taken through one of the rolls shown in Fig. 2, to illustrate details of construction thereof;

Fig. 6 is a sectional view taken on line VI—VI of Fig. 1;

Fig. 7 is a similar section taken on line VII—VII of Fig. 1;

Fig. 8 is a perspective view of a detachable bearing member employed for one of the forward rolls; and

Fig. 9 is a view similar to Fig. 6 showing the invention applied to a different type of dispenser.

Referring to the drawings in detail, the towel dispenser of the present invention is shown as

2

including a housing of the type adapted to be secured to a wall in a convenient position for dispensing operations. This housing, which is constructed with a view to providing simplicity, ruggedness, and general accessibility for adjustment and servicing, comprises what may best be termed an inner housing and a cover member therefor. The inner housing consists of a back plate 10 (see Fig. 7) which may be secured against a wall by any conventional means, and a bottom plate 11, preferably formed integrally with and extending forwardly from the lower edge of the back plate. Secured to the back and bottom plates are side plates 13 and 14 (see also Fig. 1), which side plates are set inwardly a short distance from the outer edges of the back and bottom plates and provided with outwardly projecting flanges 15 which extend all of the way around the side plates so that the side walls of

10 the housing are in fact recessed from their outer sides to provide spaces within which may be disposed substantially all of the mechanism by means of which the toweling is dispensed.

Each of the recessed outer sides of the side plates 13 and 14 is preferably covered by inwardly flanged cover plates 16 and 16a, respectively, which telescope into the recesses of the side plates and form enclosures for the towel dispensing mechanism. The cover plates 16 and 16a are secured to the side plates by means of screws such as indicated at 18, which extend through the cover plates and are threaded into the side plates. These screws are preferably of a type which may be removed only by a special tool, so that it will be impossible for unauthorized persons not provided with such a tool to gain access to the paper supporting and feeding mechanism. Any screw designed for this purpose may be used, and one suitable type is known as the "Phillips" screw, in which the head of the screw is provided with a cross-shaped recess requiring a specially designed screwdriver for its insertion or removal.

The housing is purposely left open throughout substantially its entire forward and upper faces to permit insertion of rolls of paper toweling of large diameter to be dispensed therefrom. The entire forward and top portions of the cabinet are, however, enclosed by a hinged cover member indicated at 17 in Fig. 7, which cover member also includes side panels 20 (see Fig. 1), which are pivoted as by pins 19 adjacent the lower edge of the housing so that the cover may be swung about these pins to an open position where it will depend downwardly from the pins

and permit ready access to the interior of the housing. The cover member 17 is preferably held in its closed position by latch or lock means, as generally indicated at 21.

A roll of paper toweling to be dispensed from the housing is supported between the inner side walls 13 and 14 thereof, as illustrated in Figs. 1 and 6. The roll is illustrated at 40 as wound upon a conventional hollow core 41 of pasteboard or similar material. At the end adjacent the inner wall 14 a fitting 42, which may be formed of pressed metal, is secured into the core and projects from the outer end thereof a sufficient distance to form a short trunnion received in the slot of a guide plate 43, which is secured to the inner surface of the wall 14 and which slot opens upwardly and outwardly from the normal position of the center of the core in order that a roll of paper may conveniently be inserted and removed therefrom. At the opposite end of the roll 40 a trunnion 45 extends into the open end of the core to form a connection permitting rotation of the roll. This trunnion is supported on a resilient plate 46 which is secured as by screws 47 at its lower end to the outer surface of the wall 13, and which, adjacent its upper end, has an inwardly bent portion 48 which extends through the wall 13. In order to remove the roll, the resilient plate 46 is swung outwardly until the trunnion 45 is withdrawn from its position within the core so that the entire roll, or the core from which all the paper has been withdrawn, may be moved upwardly in the direction of the slot formed in the plate 43 on the wall 14.

The recess in the wall 13 through which the portion 48 of the resilient plate 46 extends, is formed by pressing or punching outwardly two of its edges, which form guide walls 49 (see Figs. 1 and 7), between which the resilient plate 46 is guided, and these guide walls are in turn provided with inwardly punched tongues 50 which serve to limit the outward movement of the resilient plate and therefore prevent its being broken or sprung beyond its resilient limits.

While the weight of a new roll of paper toweling is sufficient to maintain the trunnion 42 in the lower end of the slot in which it rotates, there is some possibility, due to the fact that the roll becomes light as the supply of toweling is depleted, that dispensing operations are likely to result in its becoming dislodged or misplaced. Therefore, in order to prevent accidental removal of the trunnion from the lower end of the slot in which it rotates, and likewise to prevent malicious removal of the roll of toweling by persons unfamiliar with the construction of the dispenser, the present invention provides means to retain the trunnion in the lower end of the slot in the form of a metal ear 51 projecting at right angles from the wall 14 and preferably formed by punching out a wedge-shaped portion of said wall to project into the outer open end of the trunnion 42, as best shown in Figs. 1 and 6. The ear tapers toward its upper or forward end and is formed at substantially right angles to the wall at its lower end so that as the roll of toweling is inserted, the trunnion 42 will ride over the ear until it is aligned therewith, at which time the pressure of the resilient plate 46 on the opposite end of the roll will bring it into position with the outer edge of the trunnion bearing for rotation in the lower end of the slot in the member 43 which receives it.

In order to remove the core of the roll after

the supply of toweling has been depleted, it is necessary, therefore, to withdraw the resilient plate 46 sufficiently to permit the core to be moved to the left, where the trunnion 42 will clear the ear 51 before it is withdrawn.

With the roll of toweling supported for rotation in the manner just described, the free end thereof is led downwardly as shown at 55 in Fig. 6, and trained over a dispensing roller 56 so that its outer edge may project over a serrated tearing edge 57 which forms one edge of an opening in the bottom of the dispenser. A pressure roller 58 engages the paper at approximately its line of contact with the dispensing roller 56 so that upon rotation of the dispensing roller, the paper will be fed outwardly through the bottom of the dispenser, and when a measured length of toweling has been projected, it may be torn off against the tearing edge 57.

The position of the pressure roller 58 relative to the dispensing roller 56 is important in insuring against the paper becoming torn at a point within the machine that will prevent its proper feeding on a subsequent dispensing operation. As best illustrated in Fig. 6, the pressure roller 58 is above the dispensing roller so that the line of contact between the rollers is near the top of the dispensing roller. Consequently, the leading edge of the paper toweling extends around the greater part of the forward face of the dispensing roller before it passes outwardly through the opening in the bottom of the cabinet. Because of the friction between the paper and the large area over which it contacts the dispensing roller after it leaves the point of contact between the dispensing roller and the pressure roller, it is impossible to tear the paper by a direct pull at a point behind the rollers. Consequently, in the event of a user pulling downwardly on the towel which has been advanced from the dispenser, instead of drawing it against the serrated tearing edge 57, the pull will not be transmitted to the toweling behind the rollers but will tear at some point forward of the line of contact between the rollers, so that upon the next dispensing operation, the remaining toweling will be held between and advanced by the operation of the rollers.

The serrated tearing edge 57 is formed on a curved plate 59 (see Figs. 2 and 6) which is permanently secured between the lower forward edges of the side members 13 and 14, and at its upper edge the plate 59 has a plurality of fingers 60 cut and pressed therefrom to project upwardly into grooves 61 formed at spaced intervals in the pressure roller 58. These fingers serve as guides to facilitate leading the free edge of the paper 55 to its proper dispensing position between the rolls, and the plate 59 is so curved that it will also serve as a guide to cause the paper to follow around the outer surface of the dispensing roll 56. This plate, as shown in Fig. 6, is spaced from the dispenser roll a distance which increases toward its lower or tearing edge so as to insure against any possibility of the paper becoming crumpled and jammed as it is being fed outwardly.

In order to prevent the free edge of the paper from continuing around the dispensing roll 56 instead of being projected outwardly through the slot in the bottom of the dispenser, fingers 62 project upwardly into grooves 63 formed at spaced intervals in the dispensing roller 56. These fingers 62 are preferably punched and bent from the edge of a plate 64 permanently secured to the bottom of the dispenser.

A modification in the manner in which the paper is arranged in connection with the rollers is illustrated in Fig. 9 and is applicable to a type of dispensing cabinet in which the supply roll of paper is supported on inclined ledges within the cabinet. As shown in Fig. 9 the supply roll 40 rests on a pair of ledges, one of which is shown at 43a, these ledges being arranged one on each of the opposite side walls of the cabinet. These ledges are inclined forwardly so that the supply roll rests against the inner surface of the dispensing roller 56a and thus presents the added advantage of an even greater area of contact between the paper and the dispensing roller, the area being increased by the distance between the line where the supply roll contacts the dispensing roller and the line where the pressure roller contacts it. In this modification the plate 59a serves the purpose of the plate 59 in Fig. 6 and carries a tearing edge 57a, corresponding to the tearing edge 57. Fingers 60a extend into the grooves of the roller 58.

The arrangement of the dispenser and pressure rollers herein disclosed as well as the passage of the paper over said rolls and out of the cabinet are all disclosed in my copending application filed March 28, 1941, Serial No. 385,659, of which the present application is a continuation in part.

It has been found in practice that upon feeding a strip or web of paper between rolls such as those described, there is often a tendency for the paper to be fed to one side or the other or to be fed toward the center from both sides, with the result that the paper becomes bunched and wrinkled as it is dispensed. The principal reason for uneven feeding and crowding of the paper web between feeding rolls is misalignment or warping of the rolls to the extent that the pressure between the rolls varies at different points. Consequently, the paper toweling, which is usually of soft texture or crinkled to enhance its absorbent qualities, becomes compressed or lengthened at the point of greatest pressure between the rolls and consequently is fed more rapidly at some points than it is at others. In order to provide for release of the paper at frequent intervals throughout its width, and thereby to insure its self-adjustment and even feeding, one of the rolls, and preferably the smaller or pressure roll 58, has its contacting portions, or portions between the slots 61, cut away or relieved so that they will engage with the paper at alternating times during rotation of the roll. This is best illustrated in Figs. 2 to 5, inclusive, wherein the two central contacting members, marked *a*, have a full circular periphery, as shown in Fig. 3. The next rollers, spaced outwardly from the central rollers, as well as the rollers on the outermost end, all marked *b*, have their peripheries cut away throughout approximately 160°, as illustrated in Fig. 5, while the rollers *c*, intermediate the pairs of rollers *b*, are cut away throughout approximately 160°, but in a different cyclic position, as illustrated in Fig. 4. Consequently, upon rotation of the rollers to advance the paper web, the central portions *a* engage the paper continuously, while the roller *b* and *c* engage the paper alternately so that any unevenness in the feed and any tendency for the paper to become misaligned will be corrected by self-adjustment of the paper as it is periodically released at different points throughout its width.

The dispensing roller 56 is mounted in bear-

ings which facilitate its removal, which give it a bearing support, and which may readily be replaced upon the event of wear. As illustrated in Figs. 2 and 7, the roller 56 is provided with trunnions 64 projecting outwardly from its opposite ends and journaled in disc-like bearings 65 which are positioned with respect to the side walls 13 and 14 by inwardly projecting members 66 which extend into suitably positioned perforations in the side walls. These bearings 65 are held in place against the outer surfaces of the side walls by plates 67 which may be formed of spring steel or any suitable strip of sheet metal bent to overlie the bearings 65 and to have lower edges 68 bent inwardly and downwardly to project through slots 69 formed in the walls 13 and 14. At their upper ends the plates 67 are perforated to embrace ears 70 which project outwardly from the outer surfaces of the walls 13 and 14, and which are perforated for the reception of cotter keys 71, or other suitable securing means to secure the bearing discs in place.

The pressure roller 58 is also mounted in replaceable bearings which permit of its easy assembly and removal, and which are combined with resilient means for urging it into contact with the dispensing roller 56. The construction of these bearings is illustrated in Figs. 2, 7 and 8, wherein the roller is shown as provided with journals 73 projecting from its opposite ends and fitting in notches which form half bearings in the lower end of a U-shaped lever 74. This lever is pivotally supported on a pin 75 which projects through holes 76 formed in the lever and also through aligned holes formed on the side walls of the housing and in a plate 77 secured to and spaced from the outer side of each of the walls 13 and 14. Openings 78 in the walls 13 and 14 receive and permit the connected ends of the lever 74 to oscillate about the pin 75, and a spring 79 forming a connection between the lever and the housing normally urges the forward end of the lever downwardly so that the roller 58 journaled in the half bearings in that end of the lever is pressed against the dispensing roller 56.

The pressure roller so mounted may be readily removed by pressing downwardly on the inner end of one of the levers 74 so that its journal may be removed from the half bearings at the outer end of the lever, and the roll swung outwardly from that bearing and then pulled longitudinally from beneath the opposite bearing. As shown in Fig. 7, a cotter key 80, or similar pin, may be disposed across the opening 73 normally to prevent downward swinging of the lever 74 and consequently to prevent removal of the roller. This cotter key 80 is disposed on the outside of the side wall 13 and is concealed between this wall and the cover plate 16 to prevent removal of the roll except after removal of said cover plate.

The dispensing roller 56 is rotated to effect ejection of a length of toweling from the housing, so that it may be torn off along the tearing edge 57, by means of a small gear 81 (see Figs. 2 and 6), secured to an end of the dispensing roller, as by means of pins 82 extending through the gear and driven into the body of the roller itself, and meshing with a large gear 83 secured with respect to a shaft 84 which extends transversely of the housing and is journaled at one end in a removable bearing 85 (see Fig. 1) which is identical in construction with the bearings used on the dispensing roller. The opposite end of the shaft 84 projects through the housing and terminates in an

operating crank 87. This crank is preferably bent from the same material of which the shaft 84 is formed, and the shaft is provided with a flange 88 exterior of the housing, positioned to interrupt any moisture which might drain down the operating crank and prevent such moisture from entering the housing where it might cause rust or deterioration of the operating mechanism.

Adjacent the end of the shaft on which the operating crank is formed it is surrounded by a bushing 89 which is splined to the shaft and which has a head 90 on its outer end and a nut 91 threaded to its inner end. The driving gear 83 and a hardened journal collar 92 are assembled on the bushing 89 and secured between the head 90 and nut 91 by tightening of the nut. A cotter pin 93 may be provided to prevent longitudinal sliding of the bushing 89 on the shaft 84. The hardened journal collar 92 is received for rotation in a bearing 94 which is in the form of an annulus swaged over the edge of a suitable opening in the wall 14 of the housing. Ample space is left at the head end of the bushing 89 to accommodate the control mechanism for retarding or delaying dispensing operations of the crank 87, as is common practice in dispensers of this kind. No such mechanism is disclosed herein, however, as it has no direct bearing on the operation of the present invention.

As heretofore stated, the fitting 42, shown in Fig. 1, which projects from an end of the roll of paper to form a trunnion, is preferably formed of metal. In order to avoid rough exposed edges and also to provide a durable and smooth bearing surface, the outer edge of this trunnion is flanged or bent inwardly upon itself, as shown. In this manner a smooth and durable surface is formed to bear against the ear 51 when necessary, though the trunnion be formed inexpensively by being stamped from relatively thin metal.

Having thus described my invention, what I claim and desire to secure by Letters Patent is:

1. The combination with a cabinet for dispensing paper toweling or the like from a roll, of a dispensing roller adjacent the front and bottom of the cabinet, a pressure roller having annular grooves therein and mounted above and in contact with the dispensing roller and portions of the pressure roller between the annular grooves being relieved part way around the roller, such relieved portions being circumferentially spaced with respect to each other, to permit adjustment of the paper between the rollers as it is being advanced thereby, a guide fixed to the interior of the cabinet and positioned to confine the toweling between the guide and the friction driving roller and having projections extending into the pressure roller grooves, said guide directing the toweling through an opening formed in the bottom of the cabinet.

2. The combination with a cabinet for dispensing paper toweling or the like from a roll, of a dispensing roller adjacent the front and bottom of the cabinet, a pressure roller mounted above and in contact with the dispensing roller, and a fixed guide positioned to confine the toweling between guide and the friction driving roller,

said guide forming with the dispensing roller a throat widening progressively from the pressure roller to an opening formed in the bottom of the cabinet, the lower edge of said guide being serrated to form severing means for the paper.

3. In a cabinet for dispensing paper towels or the like, a feed roller extending between relatively thin metal side walls, trunnions on said roller, bearing members therefor fitting in perforations on the side walls and having shoulders engaging the walls, and removable plates retaining the bearing members in position in said perforations.

10 4. In a cabinet for dispensing paper toweling or the like and having sheet metal side walls, means for supporting rotatable shafts extending through said side walls comprising shouldered bearings received by perforations in the walls, and plates detachably secured to the walls and overlying the bearings to retain them against displacement.

15 5. In a cabinet for dispensing paper toweling from a roll, a dispensing roller journaled in the cabinet and over which the toweling passes, and a guide plate fixed to the cabinet and spaced from the surface of the dispensing roller to provide a throat between plate and roller widening toward the end through which the toweling emerges, the lower edge of the plate forming a tearing edge for the toweling and lying under the central portion of the roller.

20 6. In a cabinet for dispensing paper toweling from a roll, a dispensing roller journaled in the cabinet and over which the toweling passes, a curved guide plate spaced from the surface of the dispensing roller to provide a throat between plate and roller widening toward the end through which the toweling emerges, the lower edge of the plate forming a tearing edge for the toweling and lying in fixed position under the roller so that a downward pull on the end of the protruding toweling draws the toweling strip against the under side of the dispensing roller and the tearing edge.

25 7. In a cabinet for dispensing paper toweling from a roll, a dispensing roller journaled in the cabinet and over which the toweling passes to an opening in the cabinet, a pressure roller journaled in the cabinet to press the toweling against the dispensing roller, and a guide plate fixed to the cabinet and spaced from the surface of the dispensing roller to form therewith a throat progressively widening from the pressure roller to said opening.

30 8. In a cabinet for dispensing paper toweling from a roll, a dispensing roller journaled in the cabinet and over which the toweling passes to an opening in the cabinet, a pressure roller journaled in the cabinet to press the toweling against the dispensing roller, and a guide plate fixed to the cabinet and spaced from the surface of the dispensing roller to form therewith a throat progressively widening from the pressure roller to said opening, the lower edge of the plate forming a tearing edge on which the toweling may be severed.

PHILIP A. WOOSTER.
